(57) **CLAIM**

The ornamental design for robotic vacuum cleaner, as shown and described.

DESCRIPTION

1. Robotic vacuum cleaner
- 1.1 is a perspective view showing the robotic vacuum cleaner of my design;
- 1.2 is a front elevational view thereof;
- 1.3 a rear elevational view thereof;
- 1.4 is a left side elevational view thereof;
- 1.5 is a right side elevational view thereof;
- 1.6 is a top plan view thereof; and
- 1.7 is a bottom plan view thereof.

The broken lines illustrate portions of the robotic vacuum cleaner and form no part of the claimed design.
